UNITED STATES PATENT OFFICE.

JAMES A. GUY, OF SEMIWAY, KENTUCKY.

BUTTONHOLE ATTACHMENT.

Application filed April 3, 1925. Serial No. 20,565.

This invention appertains to sewing machines and more particularly to a novel button hole attachment therefor.

The primary object of the present invention is the provision of a novel button hole making attachment for the usual type of domestic or household sewing machine, whereby button holes can be readily made on a sewing machine in the home, without necessitating the working of the button holes by hand.

Another object of the invention is the provision of a novel button hole making attachment for domestic sewing machines embodying novel means for associating the same with the presser bar of the machine and novel means for operating the same from the needle bar of the sewing machine.

A further object of the invention is the provision of a novel button hole making attachment for domestic sewing machines embodying a novel presser foot adapted to reciprocate transversely of the work feeding bars, for moving the work relative to the needle during the forming of the stitches, whereby the zig-zag button hole stitches will be formed, novel means being provided for reciprocating the novel presser foot from the conventional needle bar.

30 A further object of the invention is to provide a novel means for constructing the attachment whereby the same can be readily attached with the conventional type of domestic or household sewing machine.

35 A still further object of the invention is to provide a novel button hole making device for sewing machines of the above character, which will be durable and efficient in use, one that will be simple and easy to manufacture and one which can be placed upon the market and incorporated with a sewing machine at a small cost.

With these and other objects in view, the invention consists in the novel construction, arrangement and formation of parts, as will be hereinafter more specifically described, claimed, and illustrated in the accompanying drawings, in which drawings:

Figure 1 is a side elevation of the improved attachment showing the same connected with a conventional sewing machine.

Figure 2 is a section taken on the line 2—2 of Figure 1 looking in the direction of the arrows, showing the novel attachment in plan, the needle bar operating lever being shown broken away,

Figure 3 is a perspective view of the complete attachment,

Figure 4 is a longitudinal section through the improved attachment, 60

Figure 5 is a horizontal section through the attachment taken on the line 5—5 of Figure 4 looking in the direction of the arrows,

Figure 6 is a horizontal section taken on 65 the line 6—6 of Figure 4 looking in the direction of the arrows,

Figure 7 is a detail transverse section through the operating lever taken on the line 7—7 of Figure 6 looking in the direction of 70 the arrows,

Figure 8 is a detail perspective view showing one of the novel spring members for normally holding the head of the operating lever in a central position, 75

Figure 9 is a detail perspective view of the operating head,

Figure 10 is a detail horizontal section through the needle bar taken on the line 10—10 of Figure 1 looking in the direction 80 of the arrows illustrating the means of connecting the operating lever with the said needle bar,

Figure 11 is a detail perspective view of the novel presser foot, 85

Figure 12 is a detail perspective view of the forward end of the base plate of the attachment, and

Figure 13 is a detail bottom plan view of the presser foot plate. 90

Referring to the drawings in detail, wherein similar reference characters designate corresponding parts throughout the several views, the letter A generally indicates the novel button hole making attachment for a conventional domestic sewing machine B.

The sewing machine B can be considered of any conventional household type and includes the usual head or arm 15 carrying the 100 depending reciprocating needle bar 16 and presser foot bar 17. This presser foot bar is adapted to be raised and lowered toward the work by means of the usual cam lever 18. The needle is adapted to be reciprocated toward the bed plate 19 on the sewing machine in the ordinary way which carries the usual throat plate 20 and reciprocating work feed bars 21. The needle 22 is held on the needle bar in the usual manner, by 110 means of a set screw 23.

In accordance with this invention, when

it is desired to use the novel attachment A with the sewing machine B, the conventional presser foot (not shown) is removed from the presser foot bar 17 and the attachment A is substituted therefor, as will be described.

The novel attachment A embodies a base plate 25 having its forward edge provided with a depending guide flange 26 for the novel reciprocating presser foot 27. At the point of juncture of the guide flange 26 with the base plate 25 inwardly directed end guide slots 28 are formed and these slots receive guide flanges 29 and 30 formed on the presser foot. As clearly shown in Figure 3 the guide flange 29 is bent laterally to engage the upper face of the base plate 25, while the flange 30 is continued above the base plate and provided with the slot 31 for a purpose, which will be later described. The presser portion 27 includes the horizontally disposed presser plate 32 provided with the elongated needle receiving slot 33 and the outwardly extending right angularly disposed guide plate 34, which carries flanges 29 and 30 heretobefore described. It is to be also noted that the guide plate 34 of the novel presser foot 27 carries outwardly directed guide flanges 35 for engaging the outer face of the depending guide flange 26 of the base plate 25. The base plate 25 carries any preferred type of means for connection with the presser bar 17 and this means varies according to the shape of the presser foot bar. In the drawings, the presser foot bar 17 is shown polygonal shaped in cross section and the plate 25 is provided with a rigid socket 36 polygonal shaped in cross section for receiving the said presser bar and this socket is provided with a set screw 37 for impinging against the presser bar. The base plate 25 embodies the rearwardly directed elongated flat arm 40, the side edges of which are provided adjacent to the rear end of the arm with upstanding pivot ears 41. The upper terminals of the pivot ears 41 carry a transverse pivot shaft 42 which rockably receives the yoke 43 of the operating lever 44. The yoke 43 is provided with a forwardly extending U-shaped socket 45 for receiving the rear end of the lever 44 and the rear end of the lever is notched as at 46, as can be clearly seen by referring to Figure 4 of the drawing. It is to be noted that the lever 44 is riveted as at 47 or otherwise secured to the yoke, so that the yoke and lever operate as a unit. The U-shaped shank or socket 45 in connection with the notched end 46 of the lever 44 defines a pocket for receiving the cylindrical shank 48 of the rocking arcuate head 49, which extends downwardly and rearwardly toward the base plate 25 for a purpose which will be hereinafter more fully described. The rocking head 49 is provided

with an enlarged opening 50 through which extends the cross or pivot shaft 42 and the head is adapted to rock on its own axis on the said cross shaft and in the pocket defined by the socket as well as to operate on the shaft 42 in a vertical plane with the lever 44. This rocking head 49 is maintained in a centralized position relative to the lever 44 and in the same vertical plane therewith by means of leaf springs 51 which are arranged on opposite sides of the rocking head and in engagement therewith. The springs 51 are retained in position, by having their inner ends inserted in the said socket 45. By this construction it can be seen that when the rocking head 49 is rocked to one side or the other against the tension of the said springs 51, that the springs will normally tend to return the head to its normal centralized position. The extreme forward or free end of the lever 44 is provided with an angular slotted head 52 which is adapted to receive the set screw 23 of the needle bar 16. This head is adapted to slide on the set screw during the reciprocation of the needle bar and the reciprocation of the needle bar oscillates the lever on the cross or pivot shaft 42, whereby the arcuate head 49 will be swung toward and away from the arm 40 of the base plate 25. Rockably mounted on the upper face of the arm 40 adjacent to the rear end thereof is a pivoted cam plate 53. This cam plate 53 is mounted upon a pivot pin 54 which is also in alinement with the longitudinal axis of the operating lever 44. The outer end of the cam plate 53 is provided with a pointed extension 55 to define the side inclined faces 56 and these inclined faces 56 terminate in recesses 57. The inner end of the cam plate 53 is pivotally connected as at 58 to the inner end of the swinging lever 59 which is disposed on the upper face of the said arm 40. This swinging lever 59 is rockably and slidably mounted at a point intermediate its ends on a pivot pin 60, which is adjustably carried by the arm 40. This pivot pin is adjustable in order to vary the throw of the lever and this pivot pin extends through a slot 61 formed in the said arm. The lever itself is provided with a longitudinally extending slot 62 in order to permit the same to slide on the said pivot pin. The forward end of the swinging lever 59 is provided with a laterally extending arm 63 which is mounted within the slot 31 formed in the flange 30 of the reciprocating presser foot 27. It is to be also noted at this point that the pivots 54, 58 and 60 are in longitudinal alinement.

In use of the improved device, the conventional presser foot is removed from the presser bar 17, as heretobefore described, and the lower end of the bar is placed within the socket 36 and the set screw 37 is adjusted so as to impinge against the bar. The slotted

arm 52 of the operating lever 44 is now placed in engagement with the set screw 23 of the needle bar 16, after which the goods is placed on the bed plate 19 of the machine 5 in the ordinary manner. The cam lever 18 is now operated so as to move the presser bar downward and the presser foot 27 in engagement with the work. The machine is operated in the desired manner and during 10 the reciprocation of the needle bar 13, the presser foot 27 will be slid transversely thereof and the toothed or lower face of the bar will move the fabric transversely of the bed plate, so that a zig-zag button hole stitch 15 will be formed in the goods. As the needle bar 16 moves upwardly and carries with it the operating lever 44, the rockable head 49 movable therewith will be swung downwardly and inwardly about its pivot 42 and 20 upon said movement, the said head 49 will engage one of the inclined faces 56 of the cam plate 53. The said head moving along the inclined face will also be moved laterally and when it engages the recess 57, it will 25 cause the cam plate 53 to be rocked on its pivot 54, this rocking of the cam plate also causing the swinging lever 59 to be moved and this movement will in turn move the presser foot 27 laterally to shift the work. 30 When the needle bar 16 is then moved downwardly, the rockable head 49 will be moved upwardly and rearwardly and when the same passes beyond the pointed extension 55, it will be forced by the spring under tension 35 over and in engagement with the opposite inclined face, so that upon upward movement of the needle bar, the operation will be repeated and the cam lever moved in the opposite direction. The spring in question 40 is placed under tension as the rockable head is moved laterally upon its engagement with the inclined face. Thus, it will be seen that upon this repeated operation, a zig-zag button hole stitch will be formed in the 45 goods. After the button hole has been formed, it is merely necessary to operate the cam lever 18 and remove the goods from the bed plate. The goods can be now cut by any suitable implement between the rows of 50 stitching to form the holes.

From the foregoing description, it can be seen that I have provided an exceptionally simple and durable button hole making attachment for a conventional domestic sewing machine.

Changes in details may be made without departing from the spirit or the scope of this invention, but:—

What I claim as new is:

1. In a sewing machine attachment of the class described, a supporting plate, a presser foot slidably associated with the plate for engaging the work and movable transversely thereof and having a needle receiving slot formed therein, an operating lever rockably mounted upon the supporting plate, a swinging lever rockably and slidably mounted upon the supporting plate at a point intermediate its ends, means operatively connecting the forward end of the swinging lever 70 with the presser foot, a cam plate pivotally associated with the supporting plate, means pivotally connecting the cam plate and the swinging lever, and means for operating the cam plate from said operating lever. 75

2. A button hole making attachment for sewing machines comprising a supporting plate, a reciprocatory presser foot associated with the supporting plate for movement transversely thereof and having a roughened work engaging face, an operating lever rockably mounted upon the plate, a cam plate pivotally mounted upon the upper face of the supporting plate having a rearwardly extending pointed extension defining oppositely inclined faces terminating in pockets, a rockable head carried by the lever provided with means for engaging the inclined faces of said cam plate, and resilient means engaging the opposite faces of the rockable head for holding the same in longitudinal alinement with the lever, and means operatively connecting the cam plate with the reciprocatory presser foot. 90

3. As a new article of manufacture, a button hole making attachment for sewing machines comprising a supporting plate having a guide flange at the forward end thereof, a presser foot slidably mounted upon the flange transversely of the supporting plate having a lower roughened work engaging surface and a needle receiving slot, a cam plate pivotally mounted upon the upper face of the supporting plate having oppositely inclined faces terminating in pockets on each side of the longitudinal center of said cam plate, a lever slidably and pivotally mounted at a point intermediate its ends upon the supporting plate, means for adjusting the pivot of the swinging lever on said supporting plate, means pivotally connecting the swinging lever and the cam plates together, means connecting the forward end of the swinging lever with the presser foot, an operating lever pivotally mounted at its rear end on said supporting plate, a forwardly extending slotted head formed on the forward end of the operating lever for connection with the reciprocatory needle bar of the sewing machine, means connecting the supporting plate with the presser foot bar of the sewing machine, a head rockably carried by the operating lever having a depending arm for engaging the inclined faces of the cam plate, and spring means normally holding the rockable head in longitudinal alinement with said operating lever. 110

4. In a sewing machine attachment of the class described, a supporting plate, a presser foot associated with the plate and slidably

100

105

110

115

120

125

130

transversely thereof, an operating lever pivotally mounted upon the supporting plate, a rockable head also mounted upon said supporting plate intermediate its ends and operable upon movement of said operating lever, a cam plate pivotally associated with the supporting plate and adapted to be engaged by said head, and a swinging plate rockably and slidably mounted upon said supporting plate for operating the presser foot upon movement of the said cam plate.

5. In a sewing machine attachment of the class described, a supporting plate, a presser foot slidably associated with the plate for engaging the work, an operating lever pivotally mounted upon the supporting plate, a rockable head also mounted upon the supporting plate intermediate its ends and having connections with the operating lever, a 15 cam plate pivotally associated with the supporting plate, and a swinging plate rockably and slidably mounted upon the supporting plate and connected with the said cam plate and presser foot.

20 6. In a sewing machine attachment of the class described, a supporting plate, a presser foot slidably associated with the plate for engaging the work, an operating lever pivotally mounted upon the supporting plate, a 25 rockable head also mounted upon the supporting plate and being connected with said

operating lever, a cam plate pivotally associated with the supporting plate, a swinging plate mounted upon the supporting plate and having connections with the said cam plate and presser foot, and resilient means 35 for throwing the rockable head from one side of the cam plate to the other side thereof upon operation of the operating lever.

7. In a sewing machine attachment of the class described, a supporting plate having a guide flange at the forward end thereof, a presser foot slidably mounted upon the flange transversely of the supporting plate, a cam plate pivotally mounted upon the supporting plate, a swinging lever slidably and pivotally mounted at a point intermediate its ends upon the supporting plate, means for adjusting the pivot of the swinging lever on said supporting plate, means pivotally connecting the swinging lever and the cam plate together, means connecting the forward end of the swinging lever with the presser foot, an operating lever pivotally mounted upon the supporting plate, and a 45 head rockably carried by the operating lever and adapted to oscillate the cam plate upon its pivot upon operation of the operating lever.

In testimony whereof I affix my signature.

JAMES A. GUY.
